UNITED STATES PATENT OFFICE.

FRANK L. CAPPS, OF BROOKLYN, NEW YORK.

ATTACHMENT FOR SOUND-BOXES.

1,399,003.

Specification of Letters Patent.

Patented Dec. 6, 1921.

Application filed May 10, 1919. Serial No. 296,134.

To all whom it may concern:

Be it known that I, FRANK L. CAPPS, a citizen of the United States, and a resident of Brooklyn, New York, (whose post-office address is No. 392 Clinton avenue, Brooklyn, New York,) have invented a new and useful Attachment for Sound-Boxes, which invention is fully set forth in the following specification.

10 This invention relates primarily to sound-boxes for playing the well-known zigzag sound records; but the underlying principles of the invention can be utilized in connection with sound-boxes for playing 15 other types of records. The object of the invention is to modulate the audible reproduction, so as to play one record or selection more softly, and another more loudly, or to play the same record more softly on one 20 occasion and more loudly on another,—without in any case distorting the music.

The invention comprises broadly a plurality or series of interchangeable attachments, each readily securable to and removable from the sound-box, and each comprising its own particular stylus-bar or lever fulcrumed thereon, each lever (with its stylus or needle) differing from the others in the series (as in dimensions or material, 30 or both), so as to produce (with its needle) the softer or the louder playing as the case may be.

The invention comprises further the individual attachment that provides an ever-fulcrumed stylus-lever or that constitutes a detachable fulcrum-mounting for the lever, with suitable means for readily securing said mounting and its lever in operative relation upon the sound-box. The lever can 40 be separated from the fulcrum if desired, but it is unnecessary to do so; normally the lever will remain fulcrumed upon said mounting whether the attachment as a whole is secured to or taken away from the 45 sound-box.

The invention comprises further the various features and details herein pointed out and claimed.

Heretofore one practice has been to provide the sound-conduit with a valve or throttle, by which to throttle down the sound-waves and muffle the sound. But this requires a special installation in the machine in the first place. Moreover, the co-action 55 of the record-undulations with the stylus and diaphragm results in certain dia-

phragm-movements having their own characteristic frequencies and amplitudes; and said diaphragm-movements in turn generate initially certain sound-waves which have 60 their own peculiar and characteristic properties, among them being loudness or volume. To throttle down and more or less choke off the passage of these initially-correct sound-waves, has a tendency to produce 65 interferences, echoes, etc.; and gives to the emitted sounds a dulled, deadened, muffled quality, instead of the true and clear yet merely-softened sounds sought by such attempt at modulation, and actually attained 70 by means of the present invention.

Another practice has been to make selective use of different needles, the so-called "loud-tone", "medium-tone", and "soft-tone" needles. But, to the trained musical ear, 75 this entails a distortion of the musical quality of the reproduction. The entire lever-system, comprising its central or fulcrum-portion and the needle also, is supposed to be properly designed to give true reproductions; and, to substitute merely a softer-playing needle, or a louder-playing one (while retaining the rest of the original lever-system unchanged), unbalances the leverage of the system as a whole, so that a 80 "loud" needle renders the music unduly harsh, and a "soft" needle distorts the musical results in other ways. Far better results are attained by the present invention, according to which, one entire stylus-lever 90 (which may comprise an appropriate needle) is specially designed for giving a true yet soft reproduction, another entire lever for giving an equally-true yet louder reproduction, and so on. 95

The ordinary user of a talking-machine, however, scarcely possesses the skill to dismount one stylus-lever from his sound-box and install another in its place, making the proper connection with the diaphragm. 100 The present invention takes care of this, however, by fulcruming the lever properly upon a member which is detachably secured to the sound-box in convenient manner, and by making suitable provision for insuring 105 almost automatic connection of lever and diaphragm.

The present inventor has discovered a highly-desirable method of dimensioning the stylus-levers; but as the same forms no 110 part of the present invention, it is deemed sufficient for the present to state that, in

general, the greater the rigidity throughout the lever-arms, the louder the playing, and vice versa; that the rigidity and the inertia (e. g., the mass) of one arm of the lever should more or less exactly counterbalance those of the other arm; that, within limits, the smaller the proportion of the mass (and of the attendant inertia) at the extremities of the lever, and the greater the proportion 10 of said mass at or adjacent the intermediate or fulcrum-portion, the better; and that there should be a gradual reduction of the rigidity and of the inertia (e. g., of the mass) of the lever, from the intermediate 15 or fulcrum-portion outward, toward each end (such reduction of mass tapering the lever-arms, preferably, in a concave curve or curves.)

The invention is susceptible of expression 20 in various ways. But, for the sake of clearness, one preferred embodiment is illustrated in the accompanying drawings, but merely as an example. In said drawings:

Figure 1 is a side or edge view, mainly a 25 diametric section, of a conventional sound-box, showing the new attachment in place;

Fig. 2 is a perspective, showing the inner face of the new attachment, removed from the sound-box; and

Fig. 3 is intended to illustrate the plurality of such interchangeable attachments.

The sound-box, of the usual or any suitable construction, comprises the main portion 1, and the tubular neck 2 at its rear, 35 and carries the usual, or any suitable diaphragm 3. As shown, the sound-box is provided with the offset 4, having (rectangular) plane surfaces parallel with the diaphragm, and carrying the headed or collared set-screw 5 threaded therein, for securing the attachment in place. To the center of the diaphragm is secured a lever connection or seat, here shown as a rivet or screw or other member having an overhang 40 which provides a recess for engagement with the inner end of the stylus-bar.

The attachment comprises the main portion 7 having therein a channel 8 to receive the offset 4 with snug fit, and also having the two pivot-lugs 9-9 for fulcruming the stylus-bar. The inner face of the attachment is curved concentrically with the sound-box, as indicated at 10, 10, 10; and the lower portion is transversely recessed, 55 as at 11, so as to slide snugly over and receive the shank of the set-screw.

The stylus-bar 12 is shown as provided with two trunnions 13-13 and a needle-barrel 14, in which latter a needle 15 is detachably secured as by the set-screw 16. As 60 shown, the fulcruming consists of the two cone-pointed screws 17 threaded respectively through the lugs 9-9 and bearing firmly against conical seats in the ends of the trunnions, and held by lock-nuts 18. The stylus-

bar lies radially of the diaphragm, of course; and, as shown, may lie substantially parallel thereto, as far as to the bend or elbow 19, whence it approaches the diaphragm and terminates in a toe 20, adapted to enter and engage the above-named recess in member 6. When such bend or elbow 19 is provided, the effective length of the lever-arm will preferably be such that, slightly before the block 7 has been shoved 75 all the way home upon its supporting-offset 4, the toe 20 will abut against its seat; so that, when the block 7 is shoved completely home, there will be a slight lateral stress of the depending portion of the lever-arm, 80 which insures a non-rattling engagement without any lost motion.

To remove one detachable stylus-mounting and substitute another, first loosen the set-screw 5, and then draw the attachment 85 and its stylus-bar off (radially, with respect to the sound-box); then apply the substitute attachment in radial direction, taking care that the toe 20 of its stylus enters the aforesaid seat 6, and then tighten up the set-screw.

It will be understood that the invention is not limited to the manner of fulcruming the lever upon the member or block 7, or to the particular screw-and-nut member 6 for providing the disengageable connection between the diaphragm and the lever, since any usual or preferred manner of fulcruming can be employed, and any suitable connection between the lever and the diaphragm, 95 provided the parts can be properly assembled and engaged (as by the radial-direction application of the attachment upon the offset 4), and can be readily dis-assembled.

It is further obvious that other changes 105 can be made in the construction and arrangement of the parts, without departing from the spirit of the invention.

It seems hardly necessary to state that the devices of Fig. 3, on a much smaller 110 scale, are not plotted out scientifically, and are given merely in order to convey the information that the invention contemplates the use of a plurality of interchangeable properly-fulcrumed styluses which differ 115 among themselves solely in the designing of their respective stylus-levers, and consequently in the acoustic behavior thereof when properly positioned and equipped with a suitable needle.

The invention having been thus fully set forth, what is claimed is:

1. The combination of a sound-box having an offset extension, and the diaphragm thereof provided at its center with a member affording a lever-connection such as an overhang, a block carrying two lugs and provided with a groove adapted to fit snugly upon said extension, means for securing said block firmly in position upon said extension, 120

a stylus-lever fulcrumed between said lugs and having its inner end disengageably engaging said lever connection.

2. The combination with a sound-box, a diaphragm mounted therein, a member affixed centrally to said diaphragm and affording a lever-connection such as an overhang, a demountable block, a stylus-lever mounted upon said block, said block and the inner end of said stylus-lever being readily and simultaneously engageable with said sound-box and said lever-connection respectively by movement in the direction of a radius of said diaphragm, and simultaneously and readily movable therefrom by reverse radial movement, and means for securing said block when so applied to said sound-box.
3. A sound-box comprising the combination of a frame, a diaphragm located therein, a block, a stylus-lever fulcrumed on said block, means for demountably securing said block to said frame, and means carried permanently by said diaphragm for rigidly holding said stylus-lever in operative relation thereto while permitting at will free radial engagement and withdrawal of said lever simultaneously with the mounting and demounting respectively of said block.
4. A sound-box having an offset and containing a diaphragm provided at its center with a positive mechanical engaging-device, in combination with a block readily and positively applicable operatively to and removable from said offset by direct movement, a stylus-lever fulcrumed on said block and having its free end readily and positively engageable operatively with and disengageable from said engaging-device by such direct movement simultaneously with said applying and removal respectively of said block, whereby said block with its said stylus-lever are readily interchangeable with another block carrying a specifically-different stylus-lever, and means for demountably securing the block in its said operative position.

In testimony whereof I have signed this specification.

FRANK L. CAPPS.
